Filed Mar. 12, 1973, Ser. No. 340,350

Term of patent 14 years

Int. Cl. D13—03; D8—08

U.S. Cl. D26—12

FIG. 2

FIG. 1

FIG. 1 is a front elevational view of the utility pole crossarm showing my new design. The rear being identical, and

FIG. 2 is a top plan view thereof.

The dotted lines do not form part of the design, but represent the utility pole on which the crossarm is mounted and the ceramic insulators which are carried by the crossarm for supporting conductors thereon.

I claim:

The ornamental design for a utility pole crossarm, substantially as shown and described.
